UNITED STATES PATENT OFFICE.

FRANK S. CROWELL, OF TOLEDO, OHIO, ASSIGNOR TO THE EDWARD N. RIDDLE CO., OF TOLEDO, OHIO, A CORPORATION OF OHIO.

DESIGN FOR A COMBINATION BODY AND PLATE FOR LIGHTING FIXTURES.

Application filed July 3, 1923. Serial No. 6,651. Term of patent 7 years.

To all whom it may concern:

Be it known that I, FRANK S. CROWELL, a citizen of the United States, residing at Toledo, in the county of Lucas and State of Ohio, have invented a new, original, and ornamental Design for a Combination Body and Plate for Lighting Fixtures, of which the following is a specification, reference being had to the accompanying drawing, forming part thereof.

Fig. 1 is a side view of a combination body and plate for lighting fixtures, showing my new design.

Fig. 2 is a bottom view of the same.

I claim:

The ornamental design for a combination body and plate for lighting fixtures, as shown.

FRANK S. CROWELL.
